GIUSTINO CATTANEO, OF MILAN, ITALY.

COOLING ARRANGEMENT FOR EXHAUST VALVES OF INTERNAL-COMBUSTION ENGINES.

1,415,793.

Specification of Letters Patent. Patented May 9, 1922.

Application filed April 27, 1918. Serial No. 231,283.

(GRANTED UNDER THE PROVISIONS OF THE ACT OF MARCH 3, 1921, 41 STAT. L., 1313.)

To all whom it may concern:

Be it known that I, GIUSTINO CATTANEO, employee, subject of the King of Italy, resident of Milan, in the Kingdom of Italy, No. 5 79 Via Monte Rosa, have invented new and useful Improvements in the Cooling Arrangements for Exhaust Valves of Internal-Combustion Engines, (for which I have filed an application in Italy April 18, 1917,) of 10 which the following is a specification.

This invention relates to valves, and in particular to exhaust valves for internal combustion engines. An object of the invention is to provide an improved valve structure including a cooling device whereby oil, water or any suitable cooling liquid may be circulated through the valve body and stem without interfering with the proper operation of the valve. A further 15 object of the invention is to provide means for introducing the cooling medium into the valve through the controlling mechanism therefor, in order to avoid sliding joints between the liquid feeding means and the movable valve structure.

The arrangement according this invention affords a perfect oil circulation inside the valve and permits of the difficulties concerning the tightness of the joints being 20 eliminated in the simplest way without hindering the motion of the valve itself.

The arrangement will be readily understood reference being made to the annexed drawing.

The exhaust valve a controlling the passage of the burnt gases from the explosion chamber C to the exhaust chamber D, is actuated by a cam b through the intermediary of a hollow lever c pivoting on the fixed support f which is hollow inside and communicates with the internal space of lever c through the port k . The lever c rests on the hollow valve head e , and its interior 25 communicates with the interior of head e through an opening which is preferably in alignment with the axis of the valve; this head e is capable of revolving on its guide s and serves also as an intermediary through which the valve disc is carried 30 by the spring disc d . A pipe w inside of the hollow valve stem forms an extension of e and reaches down close to the valve body, which is also hol-

low and is closed at its lower end by a removable cover m adapted to be screwed thereto.

The inside g of the fixed pivot f is connected to the delivery nozzle of an oil pump; so that the oil from the pump is forced through port k , lever duct g' inside of the lever c , inner bore z of the pipe w and ducts i over the cover m . Hence the oil is forced upwardly through the holes n formed near the edges of a diaphragm l , ducts i' , and annular spaces o between pipe w and the hollow valve stem a , and b between the upper portion of pipe w and the pipe shaped extension of disc d , 70 to the valve head e . Through ducts $p-p$ formed on the upper side of the spring disc d , it flows out of the valve structure and drops on to the partition t , whence it is returned into the pump reservoir, whereupon it is again circulated through the valve after having been cooled, if desired, by traversing a radiator of any suitable construction.

By this arrangement the oil is circulated 80 inside the stem and discs of the exhaust valve, all parts of which are thus conveniently cooled.

Further the more or less perfect tightness of the various parts in which the oil 85 is circulated does not affect the regular working of the engine, there existing no communication whatever between the circulating pressure oil and the exhaust gas chamber.

The intermediary lever c can be built as a rocking lever or as a cylindrical rod to which a rectilinear motion is imparted, that is to say the intermediary member between the valve controlling cam and the valve can be constructed in any suitable manner.

Of course also in other parts of the device the constructional details and those concerning the form may be varied from those described and illustrated without departing from the spirit and scope of the invention as set forth in the appended claims.

Having now described my invention and how the same is to be carried out, what I claim as my invention, is:

1. In an internal combustion engine, the

combination with a valve having a hollow body and stem, and a hollow valve head mounted in said stem, of a hollow actuating member engaging said valve head, the 5 engaging surfaces of said actuating member and valve head having apertures connecting the interior of said member with the interior of said valve head.

2. In an internal combustion engine, the 10 combination with a valve having a hollow body and stem, and a hollow valve head engaging said stem, of a hollow actuating lever having a recessed end closely fitting said valve head, the engaging surfaces of said 15 lever and valve head having apertures affording a permanent communication between the interior of said lever and the interior of said valve head.

3. In an internal combustion engine, the 20 combination with a valve having a hollow body and stem, and a hollow valve head engaging said stem, of a hollow actuating rock-lever extending at an angle to said valve stem, a hollow pivot for said lever

adapted to be connected to a supply of liquid, 25 said pivot having an aperture communicating with the interior of said lever, said lever engaging said valve head and having an opening communicating with the interior of said valve head.

4. In an internal combustion engine, the combination with a valve having a hollow body and stem, and a hollow valve head mounted in said stem, of a hollow cam-actuated lever extending at an angle to said 35 valve stem, a hollow stationary pivot for said lever adapted to be connected to a supply of liquid, said pivot having an aperture communicating with the interior of said lever, said lever having a recessed end 40 closely fitting said valve head, the engaging surfaces of said lever and valve head having apertures connecting the interior of said lever with the interior of said valve head, and an outlet for the liquid in said valve, 45 arranged between said valve head and stem.

In testimony whereof I affix my signature.
GIUSTINO CATTANEO.
